UNITED STATES PATENT OFFICE.

JOHN C. PUETZ, OF HINSDALE, ILLINOIS.

DESIGN FOR A GLASS JAR.

44,495.

Specification for Design.

Patented Aug. 12, 1913.

Application filed August 3, 1912. Serial No. 713,197. Term of patent 14 years.

To all whom it may concern:

Be it known that I, JOHN C. PUETZ, a citizen of the United States, residing at Hinsdale, in the county of DuPage and State of Illinois, have invented a new, original, and ornamental Design for a Glass Jar, of which the following is a specification, reference being had to the accompanying drawing, forming a part thereof.

This application relates to a design patent for glass jars.

Figure 1 is a view of the jar in side elevation. Fig. 2 is a top plan view of the jar.

The jar design comprises a body having

substantially straight vertical lines with substantially plain sides, four in number, forming panels as shown at 10 connected by curved corners as at 11, the panels 10 being rounded at the top as indicated at 12, and a rounded shoulder 13 formed at the top between the sides 10 and the neck 14.

I claim:

The ornamental design of a glass jar as shown.

JOHN C. PUETZ.
